FAN BLADE AND HUB ASSEMBLY

Karl M. Ganger, Dayton, Ohio, assignor to The Lau
Blower Company, Dayton, Ohio, a corporation of Ohio

Application April 19, 1956, Serial No. 41,129

Term of patent 14 years

(Cl. D26—7)

FIG-1

FIG-3

FIG-2

FIG-4

FIG-5

FIG-6

FIG-7

FIG-8

Fig. 1 is a perspective view looking toward the front of a fan blade and hub assembly embodying my new design;

Fig. 2 is a front elevation of the assembly of Fig. 1;

Fig. 3 is an enlarged view looking from left to right in Fig. 2 with a portion of the hub broken away in vertical section;

Fig. 4 is an end elevational view of one of the blades.

Fig. 5 is a plan view of a blade; and

Figs. 6, 7 and 8 are sections through the blade on the lines 6—6, 7—7 and 8—8, respectively, of Fig. 5.

The design is characterized by the edge portions of the blades extending in opposite directions with respect to the plane of the central portions and by the generally dome-shaped configuration of the hub assembly.

What is claimed is:

The design for a fan blade and hub assembly, substantially as shown and described.
